ATT'Y'S

UNITED STATES PATENT OFFICE.

EDWARD WATERS, OF CAPREAL, ONTARIO, CANADA.

RAILWAY-TIE.

1,392,376.

Specification of Letters Patent.

Patented Oct. 4, 1921.

Application filed August 27, 1920. Serial No. 406,431.

To all whom it may concern:

Be it known that I, EDWARD WATERS, a subject of the King of Great Britain, a resident of the town of Capreal, Province of 5 Ontario, Dominion of Canada, have invented certain new and useful Improvements in Railway-Ties, of which the following is a specification.

This invention relates to improvements in 10 railway ties, and the objects of the invention are to provide a tie which can be readily renewed or removed and replaced with a minimum of time and labor, to facilitate shimming the rails during winter when heaving 15 of the track bed is liable to take place, so that the level of the rails will be readily adjusted, to provide a false tie which may be inserted under the rails if too great a depth or thickness of shims are required to bring 20 the rail to the desired level, and generally to adapt the several parts to better perform the functions required of them.

With the above and other objects in view, 25 the invention consists essentially of the improved construction particularly described and set forth in the following specification and accompanying drawings forming part of the same.

In the drawings:

30 Figure 1 is a perspective view of my improved tie.

Fig. 2 is a front elevation of the same showing the false tie in position.

Fig. 3 is a plan view of the chocks.

35 Fig. 4 is a longitudinal section through one of the chocks.

Fig. 5 is a perspective view of the false tie as seen when collapsed.

Like characters of reference refer to like 40 parts in the several figures.

Referring to the drawings; A represents a pair of chocks each of which is formed like a frustum of a rectangular pyramid, that is to say, the end walls and side walls converge 45 toward the top.

Each of the chocks has a longitudinally extending orifice 10 therethrough, and a plurality of orifices 11 extending vertically through the chock. The ends of the chock 50 A at the orifice 10 are provided with recesses 12.

The chocks A are arranged in spaced relation and a tubular member 13 is located between the chocks and rests in the inner recesses 12 of the said chocks, and a tie rod 14

is passed through the orifice 10 of one chock, then through the tubular member 13, and ultimately through the orifice 10 of the second chock.

On the ends of this tie rod nuts 15 are 60 threaded. A washer 16 is provided, which is located between the tubular member 13 and one of the recesses 12 of a chock A, and this washer straddles the tie rod 14.

When the nuts 15 are tightened the two 65 chocks will be pulled into and positively held in the desired position relatively to each other. The chocks A are placed on the rail bed and the ballasting of the rail bed in whatever form it may be, surrounds the 70 chocks on the four sides, and the tubular member 13 may be, if desired, partially embedded in the ballasting.

On each of the chocks a suitable rail retaining member B is mounted. 75

In the event of one of the chocks A becoming worn, broken or requiring repairing, then it is only necessary to unthread the nut 15 adjacent to said chock, when the chock may be pulled outwardly and a new chock 80 placed on the tie rod 14 after which the nut 15 would be rethreaded on the tie rod.

It will be noticed that by forming the ends and side walls tapering upwardly they act as 85 anchoring means to prevent lateral or end-wise displacement of the chock, and since the walls are wedged against a ballasting or rail bed they hold the tie firmly in position.

During winter use it frequently happens 90 that the rail bed heaves so throwing it out of alinement, and the usual practice is to shim the rails to bring them into alinement or level, but it often happens that when the shims become too thick the rail will be unsafe and for the purpose of leveling the rails 95 I provide a false tie C which is elevated above and engages with the chocks A.

This false tie C comprises a pair of pivotally connected bars 17 having their adjacent ends beveled as shown at 18 and formed with 100 beveled shoulders 19 against which the ends of the adjacent bars will abut.

The ends of the bars 17 at the outer ends are cut away to form beveled shoulders 20 which will abut the inner beveled face of 105 the chocks A, and thereby prevent displacement of the false tie.

The rail retaining device B will be mounted above or on top of the false tie C, and the rails positioned in this rail retaining device. 110

The object of the washer 16 is to provide any slight adjustment of the rail relatively to each other especially at curves, when the washer may be removed if desirable to allow the rails being pulled closer together.

As many changes could be made in the above construction and many widely different embodiments of my invention within the scope of the claim constructed without departing from the spirit or scope thereof, it is intended that all matter contained in the accompanying specification and drawings shall be interpreted as illustrative and not in a limiting sense.

What I claim as my invention is:

A tie comprising a pair of chocks each formed like a frustum of a rectangular cone, means for securing the chocks in spaced relation, a false tie being provided formed with beveled shoulders on the bottom adapted to engage the inner beveled walls of the chocks.

In witness whereof I have hereunto set my hand in the presence of two witnesses.

EDWARD WATERS.

Witnesses:

MARY E. KNOX,
ETHEL GARROW.
